UNITED STATES PATENT OFFICE.

JAMES WINEGARDEN, OF GRAND RAPIDS, MICHIGAN.

BURGLAR-ALARM.

SPECIFICATION forming part of Letters Patent No. 430,979, dated June 24, 1890.

Application filed September 21, 1889. Serial No. 324,614. (No model.)

To all whom it may concern:

Be it known that I, JAMES WINEGARDEN, a citizen of the United States, residing at the city of Grand Rapids, in the county of Kent 5 and State of Michigan, have invented a certain new and useful Burglar-Alarm, of which the following is a specification.

My invention relates to a system of burglar alarms, to be applied to buildings, consisting 10 of electric circuit-closers automatically operated by pressure caused by the opening of windows or doors and also by pressure upon the window or window-sash, and may be applied in connection with stationary lines of 15 telegraph or telephone for the purpose of giving the alarm at points outside of the building to which the system of burglar-alarm is applied, the object of the invention being to cause an alarm to be given at any required 20 point by means of the construction and arrangement of parts more fully described herein. These objects are accomplished by means of the mechanism illustrated in the accompanying drawings, in which—

Figure 1 shows a front elevation of a window-sash and a part of the window-jamb, showing the circuit-closer upon the inner surface of the sash, also a circuit-closer between the jamb and the sash, and a circuit-trans- 25 ferrer. Fig. 2 is a perspective view of one edge of a window-sash, designed to show the connection of the automatic circuit-closer and metallic conducting-strips. Fig. 3 is an elevation of that portion of a window-jamb 30 which comes in contact with the window-sash, showing a front view of a circuit-closer, also the electric transfer strips. Fig. 4 is a side elevation of my automatic circuit-closer which 35 is applied to the inside of the sash, being the same device shown on the left-hand portion 40 of Fig. 1. Fig. 5 is an elevation of a sash and sash-stop with an automatic circuit-closer placed so as to be held open by means of the 45 sash; and Fig. 6 is an elevation of a window-stop, showing the position of the automatic circuit-closer when the pressure from the sash has been removed.

The sash is constructed in the ordinary manner. Near the edge of the sash is placed 50 the automatic circuit-closer shown in Fig. 1, which consists of the part 10, which is made of

fibrous paper or some non-conducting material. Attached to one end of the base or part 10 is a metallic plate 11. Attached to the other end is a metallic spring 12. This circuit-closer, constructed as above described, is attached to the window-sash between the sash and the sash-stop by means of a pin 13, or in any other suitable manner. On the edge of the sash which comes in contact with the 55 jamb I provide two metallic strips or conductors. (Shown in Fig. 2 by 5 and 6.) The metallic plate 11 is connected by a wire or other conductor to the metallic plate 6. The metallic spring 12 is connected by wire 9 to 60 the plate 5.

Upon the jamb I place two plates 8 8, which are preferably made of brass, and which are bent so as to come in contact continuously with the plates 5 and 6, one of which electric 65 connecting-plate is shown in Fig. 1. These plates serve the purpose merely of transferring the electricity from the strips 5 and 6 to the wires 21 and 22, and from thence to the 70 battery.

The operation of this part of my invention is as follows: The automatic circuit-closer 75 (shown in detail in Fig. 4) is placed upon the inside of the sash and between the sash and the strip, usually known as a "window-stop," 80 in such a manner that the spring 12 is raised a slight distance from the metal plate 20, thus holding the electric circuit open. Any pressure from the outside of the window, either upon the glass or upon the sash, will cause 85 the spring 12 to come in contact with the plate 11, thereby connecting or closing the circuit. The electricity goes to the wire 20, and from thence to one of the transfers 8, through the battery, back through the plate 5, and wires 90 9, making a complete circuit, upon which circuit is placed a bell, which bell is located at any point in the building required. This circuit-closer is peculiarly adapted to the window-sash to be operated by pressure from the 95 outside.

In Fig. 5 I have shown an edge view of the sash and of a portion of the stop. 13^a represents an automatic circuit-closer, consisting of a spring placed upon the stop, one end of 100 which is curved or bent so as to pass through the opening in the stop. The spring 13^a is a

conductor, and also the plate 12^a, both of which are connected by wires and other suitable connections to the battery. The point of contact which closes the circuit is shown 5 in Fig. 6 by 14. When the window-sash is in position, the pressure of the sash holds the spring 13^a out of connection, as shown in Fig. 5; but on removing the sash the spring automatically connects at point 14 with the plate 10 or conductor 12^a, and the electric current is completed and the bell caused to be rung. This device or circuit-closer is not only 15 adapted for use in connection with windows, but also with doors. With windows the connection is made upon the removal of the window-sash. When applied to doors, the connection is made or circuit closed when the door is open.

In Fig. 3, 7 represents a forked circuit-closer. 20 This is placed upon the window-jamb so that the upper point is somewhat above the plates 5 and 6 on the window-sash, and are so placed that when the window-sash is raised a short distance the plates 5 and 6 are brought in contact with the arms of 7, thereby connecting the circuit through the plates 5 6, electric transfers 8 8, and wires 21 22 to the battery. This portion of my invention is adapted to windows 25 or other openings which slide in grooves or otherwise.

In order to operate my invention in connection with a telephone, all that is necessary to do is to connect the wires with a telephone-wire, thus ringing the bell at the central office 30 of the telephone company. It is evident that this construction may be applied not only to single buildings, but to numerous buildings situated at a considerable distance from each other, if found desirable.

35 40 I wish it to be understood that I do not herein claim the combination, with the battery and

the electric-bell alarm, of two plates secured parallel to each other on the edge of the window-sash, a circuit-closer secured to the window-frame and two electric transfers secured 45 to the window-frame below said circuit-closer, respectively connected with the battery in the bell-circuit, and continuously in contact with the parallel plates on the sash, as such is not my invention.

50 Having thus described my invention, what I claim to have invented, and desire to secure by Letters Patent, is—

1. In a burglar-alarm, the combination of a circuit-closer, the window-sash and window-stop, and suitable connections with the battery and alarm-bell, said circuit-closer placed between the sash and stop, and adapted to close the circuit automatically in case of lateral pressure exerted from without the building 55 upon the window-sash or window-glass to move the sash toward the window-stop, substantially as described.

2. The combination, with a window-sash and a window-stop, of a contact-plate 11 and a circuit-closing spring 12, both attached to the window-sash between the latter and the window-stop, the two vertical metal plates 5 and 6, secured to the edge of the sash next to the jamb, and respectively connected with the contact-plate and the spring, the two plates 8 fixed on the jamb and continuously in metallic contact with the vertical plates on the edge of the sash, and a source of electricity and connections between the latter and the plates on 70 the jamb, substantially as described.

75 In witness whereof I have hereunto set my hand and seal in the presence of two witnesses.

JAMES WINEGARDEN. [L. S.]
